(57) CLAIM

The ornamental design for a pair of tethered animal foot covers, as shown and described.

DESCRIPTION

FIG. 1 is a perspective view of one embodiment of a pair of tethered animal foot covers showing our new design; FIG. 2 is a perspective view of the foot covers in a slightly opened condition;

FIG. 3 is a front view of the foot covers, shown ready for use with a second pair of foot covers;

FIG. 4 is a top plan view of the foot covers of FIG. 1;

FIG. 5 is a front elevational view thereof;

FIG. 6 is a left side elevational view thereof;

FIG. 7 is a right side elevational view thereof;

FIG. 8 is a bottom plan view thereof; and

FIG. 9 is a perspective view of the foot covers of FIG. 3, shown in condition of use on a dog.

FIG. 10 is a perspective view of a second embodiment of a pair of tethered animal foot covers, showing our new design;

FIG. 11 is a perspective view of the foot covers in a slightly opened condition;

FIG. 12 is a front elevational view of the foot covers, shown ready for use with a second pair of foot covers;

FIG. 13 is a top plan view of the foot covers of FIG. 1;

FIG. 14 is a front elevational view thereof;

FIG. 15 is a left side elevational view thereof;

FIG. 16 is a right side elevational view thereof; and,

FIG. 17 is a bottom plan view thereof.

In the drawings, the broken line showing of a duplicate foot cover and a dog depict environmental subject matter only and form no part of the claimed design.

The pair of tethered animal foot covers is shown with symbolic breaks in its length. The appearance of any portion of the article between the break lines forms no part of the claimed design.
